SHEDDING MOTION

George Goodline, Pawtucket, R. I.

Application March 22, 1932, Serial No. 600,390

2 Claims. (Cl. 139—74)

The object of this invention is to improve shedding mechanism of the open-shed type for looms by reducing the power necessary to operate the same in effecting the shedding action; by minimizing the jar, vibration and noise incident to such operation, and especially the jar on the harness and hence on the warp; by avoiding movement of any harness frame in such manner that the warp threads shifted will be shifted at one side 5 of the warp more than at the other; by insuring that each harness system will be quite stationary when at rest; and by obtaining movements of the harness cords which shall be direct or devoid of shifting thereof transversely of themselves, 10 such as happens in a dobby due to the pivoting movement of the cord-actuating levers. A further object is to provide simple and efficient means for rotating step by step the cylinder of a pattern mechanism useful in the control of a 15 shedding mechanism.

In the drawings,

Fig. 1 is a plan of the shedding mechanism;

Fig. 2 a side elevation;

Figs. 3 and 4 are longitudinal vertical sections on lines 3—3 and 4—4, respectively, Fig. 1; and

Fig. 5 is a section on line 5—5, Fig. 3.

A suitable frame 1 is adapted to be affixed to the arch 2 of the loom frame and the sides of this frame have the horizontal upper and lower slots 3 in which move back and forth the upper and lower knives or actuators 4 and 5. The motion of each such knife is oscillatory and such that (here) the near ends thereof have greater extent of movement than their far ends. This is obtained from an oscillated shaft 6 journaled in the frame and having fixed thereon between the frame sides two gears 7 and 8 (the nearer one 7 of which is of the greater diameter) and through 30 an upper and a lower pair of racks 9 and 10, the upper pair being pivoted to the ends of knife or actuator 4 and the lower pair to the ends of knife or actuator 5 and each rack having a projecting portion thereof at its other end penetrated and therefore guided by a horizontal rod 35 supported by and inward of the side of the frame and in effect a part of the frame (see Fig. 4). At the near side of the frame shaft 6 has affixed thereon another gear 12 (Fig. 2) upon 40 which rests and with which meshes a rack 13 which is reciprocated from some going part of the loom through a bellcrank lever 14, rack 13 being held in engagement with this gear by a roller 15 journaled in the frame and peripherally 45 grooved to receive the rack and confine it against

lateral disengagement from the gear. When lever 14 and hence shaft 6 and its gears are oscillated the knives will obviously be given the motion ascribed to them, and in opposite directions simultaneously.

The harness cords 16 may extend over guides or sheaves 17 arranged in two suitably spaced horizontal rows on the arch 2 as usual and down to the harness frames or shafts A and each two cords for a harness frame are connected to the hook 18 of and pivoted to a yoke 19 at 19a which (Fig. 5) straddles and forms a bearing for a rotary gear 20. Each such gear meshes with a pair of upper and lower racks 21 and 22. Each three intergeared elements 20—21—22 are confined as a unit to a vertical plane by the intermeshing portions of 20—21 on the one hand and 20—22 on the other (Fig. 5) being received in the guideway between two of the parallel bars 23 of a grid, such bars being affixed at their ends to end bars 1a of the frame and cross-bars 1b thereof, bars 23 and 1a and 1b in effect forming parts of the fixed structure or frame. The racks, as will appear, are to be reciprocated longitudinally, thereby to rotate and roll the gears and hence move the two harness cords and corresponding harness frame, and to prevent undesirable tilting thereof there may be other bars 1c and 1d to guide them. The right hand end of each rack 21, 22 has a hook 21a (21b) pivoted to move in a vertical plane and adapted to catch over the knives or actuators 4 and 5, respectively, thus to couple the rack with its knife, each coupling having a depending arm 23a (24a).

In the appended claims I treat each frame A, its cords 16 and the yoke 19 as a harness; and the element 20 (in effect a floating lever) and the racks 21, 22 as parts of an oscillatory system which at each side of the pivot-connection between the element 20 and yoke 19 is adapted to abut the frame at 1a—1a to limit the movement of the harness in the direction in which it is normally urged, subject to its weight; and the hooks or couplings 21a and 21b as disconnective coupling means.

At 25 is fulcrumed in the frame a series of bellcrank controller levers 26 each having a weighted horizontal arm and an upstanding arm having two lugs 26a each engaging one of the hook arms 23a (24a) in such manner that the lever tends to hold the corresponding hook, which otherwise tends to fall into engagement with the knife, elevated clear of the same, as in Fig. 3. The hooks are graduated in length (Fig. 1) for a purpose to appear.

Each lever 26 has its horizontal arm resting on a pattern chain 27 rotating with the cylinder 28. According as, in the known way, presence of a pin 27a of the chain under any lever 26 elevates the latter or absence of a pin allows the lever to fall, so the corresponding hook will be in or out of position to be caught and thereupon move forward and back with the corresponding knife or actuator.

10 *Operation.*—The weight of each harness frame tends to maintain the two racks 21 and 22 appertaining thereto back, or against bars 1a (all the racks being shown back in the drawings). If as to any one harness frame one of its racks is 15 pulled forward (to the right) the harness frame will be lifted, as an incident of the lever action of the corresponding element 20 which is here a gear and hence rolls on the two racks; if on the return of that rack the other rack is left back 20 the harness frame will fall, but if on such return of the first rack the other rack is moved forward the gear 20 will remain in its forward position rolling on the two racks idly, or without linear progression in either direction, wherefore the harness frame will remain raised. In short, once 25 a harness frame is raised it will be allowed to fall only when the rack which last moved forward moves back without the other rack being moved forward. The "calling" of the racks is 30 done by the controller lever 26, only one such device being required for each two racks, upper and lower. That is to say, if said lever, having called one rack (i. e., permitting its hook 21a or 21b to fall and catch a knife), is allowed to return to 35 hook-lifting position before the other knife assumes its backward limit, the harness frame will have been raised and immediately allowed to fall; if it remains in "calling" position on one or more return movements of the knives the harness frame will correspondingly remain raised, falling when the knife which last moved to the 40 right returns with the controller lever in the hook-elevating position, or that shown. Since the knives oscillate, or at its outward limit each 45 stands angularly related to its position at the inward limit, the desired convergence of the warp shed will result. In the present case each knife is oblique to the paths of reciprocation of the racks 21 and 22, wherefore the hooks are graduated in length as stated.

50 The leverage present in the elements 20 obviously reduces very appreciably the power necessary to lift the harness and appreciably reduces the jar, vibration and noise incident to the operation; each harness-including system stands perfectly stationary when at rest because it is then supported (at 1a) directly by the fixed structure; and the pull on each harness cord may be exerted, as shown, in direct alinement with 55 the two sheaves 17, which not only avoids the transverse shifting of the cords which attends the use of the lifting levers or jacks in an ordinary dobby but also avoids the tendency, characterizing the use of such levers, of lifting one 60 end of a harness frame somewhat more than the other, with consequent transverse inclination of the sheet of warp threads affected in at least one of its positions—up or down.

65 In the example each pair of hooks 21a—21b is 70 moved by engagement with the lever 26 to position to clear the knives and is normally urged (here by gravity) to position to be caught thereby. However, I do not wish to be limited to this rather than the reverse condition. A novel feature of my invention is as follows: Since the

arms or projections 23a of the hooks project transversely of the paths of movement of the hooks with their racks it is possible to have the movement of the hooks by lever 26 depend on their said movement with the racks, rather than on movement transmitted to or permitted them by and incident to movement of said lever; in short nice timing of the lever to have it cause movement of the hooks precisely at the instant one or the other knife is back is thus avoided. 10

15 The pattern cylinder 28 may be rotated step by step in any known way, but I prefer the following means for so rotating it:

20 On faces facing lengthwise of the axis of the cylinder (here the inner and outer faces of a disk 29 on its shaft portion 28a) are two equal-number sets of projections 30 and 30a in which those of each set are approximately equally spaced around the cylinder axis and those of one set are opposite the spaces between those of the other. 25 31 is an actuator reciprocated in any way, as from a segment 32 oscillating with lever 14, the actuator and segment having intermeshing teeth. This actuator has portions, as legs 31a, which straddle the shaft portion 28a (and may be guided thereby) and reach lengthwise of its reciprocating path and are respectively provided with two actuating projections 33 and 33a which reach in opposite directions lengthwise of said shaft and are offset from each other lengthwise of said reciprocating path, one being arranged to engage the first-named projections (30) of the cylinder one after another in the movements of the actuator in one direction and the other to engage the second-named projections (30a) of the cylinder one after another in the movements of the actuator in the other direction, thus to rotate the cylinder step by step. Thus, in Fig. 2, the actuator projection 33a, when the actuator 30 last moved to the right, encountered that (rear) projection 30a which was then in the position of the left lower front projection 30, and turned the cylinder to the position shown; when the actuator now moves to the left actuator projection 33 will encounter the right upper (front) projection 30 and turn the cylinder the same distance as before (here 45 degrees) and in the same direction; and so on. To hold the cylinder in each position to which it is thus turned it may have the usual octagonal disk 34 against which a spring-pressed lever 35 is held (Fig. 3).

40 Since the coupling changes must occur when one knife or the other is back (or at the left) the structure 14—32, from the lever portion 14 of which the movement of the knives is derived, must 45 turn the cylinder one step on each half-cycle of its complete (back-and-forth) movement.

50 Having thus fully described my invention what I claim is:

55 1. In combination, with supporting structure, a pair of backwardly and forwardly moving actuators, a pair of members slideable backwardly and forwardly in and having their backward movement limited by said structure, a floating lever operatively connecting said members, a harness connected to said lever between said members and pulling backwardly on the lever, hooks projecting forwardly from said members and respectively pivoted thereto and movable in one direction to engage and in the other to clear the respective knives and normally urged in one direction, a movable hook-moving element normally urged into the paths of backward movement of both hooks and adapted to move the hook which is backwardly moving clear of the corresponding 60 65 70 75 80 85 90 95 100

actuator, and pattern means for moving said element out of said paths.

2. The combination, with supporting structure including opposed substantially parallel grids having guideways all parallel with each other, two sets of racks movable and having their teeth housed in the guideways of the respective grids, the teeth of each set projecting toward the other set, floating levers each having toothed portions

engaged with the teeth of and in the guideways of two of the levers, one from each set, a harness connected to each lever between the ends of the latter, reciprocating actuators, one for each set of racks, each rack having a coupling movable into and out of coupled relation to the corresponding actuator, and pattern-controlled means controlling the movements of the couplings. 5

GEORGE GOODLINE.
